FEELER UNIT FOR THE CONTROL OF A TRAVELING MACHINE

Ronald M. Guntert, Wilbur F. Earley, and Robert E. Noack, Stockton, Calif., assignors to Guntert & Zimmerman Const. Div., Inc., Stockton, Calif., a corporation of California

Filed May 9, 1960, Ser. No. 27,534
5 Claims. (Cl. 336—30)

This invention relates to a feeler unit for use in the control of a traveling machine, such as a concrete slab laying machine as shown—for example—in United States Patent No. 2,864,452.

One object of the present invention is to provide a feeler unit for the purpose which is an improvement over the unit shown in the above identified patent, in that a more sensitive and accurate "feeling" action is obtained, and a greater range of movement of the probe finger is possible.

A further object of the invention is to mount the unit on a support in such a manner that a much easier and better swinging action when passing by the grade-wire supports is obtained, together with an improved arrangement to return the unit as a whole, and which includes the probe finger, to its initial or normal position after being so swung, and to then rigidly yet yieldably maintain the unit in such normal position.

Still another object of the invention is to provide a practical, reliable, and durable feeler unit for the control of a traveling machine, and one which will be exceedingly effective for the purpose for which it is designed.

These objects are accomplished by means of such structure and relative arrangement of parts as will fully appear by a perusal of the following specification and claims.

In the drawings:

FIG. 1 is an elevation of a feeler unit having a laterally extending probe finger usable for vertical control of the machine to which it is attached.

FIG. 2 is a sectional plan on line 2—2 of FIG. 1.

FIG. 3 is a fragmentary sectional elevation on line 3—3 of FIG. 2.

FIG. 4 is a top plan view of the unit on a reduced scale and partly in section, taken on a line 4—4 of FIG. 1, and showing the unit as clearing a grade-wire holding arm.

FIG. 5 is a fragmentary sectional elevation on line 5—5 of FIG. 1.

FIG. 6 is an end elevation, partly in section, of a modified form of feeler unit wherein the feeler finger is vertically disposed for lateral control or steering of the machine.

FIG. 7 is a sectional elevation of such modified unit on line 7—7 of FIG. 6.

FIG. 8 is a fragmentary sectional elevation on line 8—8 of FIG. 6.

Referring now more particularly to the drawings, particularly at present to FIGS. 1—5, and the characters of reference marked thereon, the feeler unit which is the subject of this invention is supported from a bracket (not shown) on the machine, as shown in said U.S. Patent No. 2,864,452, by means of a horizontal shank 1 which projects toward the machine in a direction away from the grade reference member such as a wire 2. Rigid with the outer end of the shank, and which is the end thereof closest to the wire 2, is a vertical sleeve 3 which engages a spindle 4 intermediate the ends of the latter, and which spindle is non-turnably secured in the sleeve.

Turnable on the spindle in vertically spaced relation are ears 5 which normally project laterally out from the spindle, or toward the grade wire, and are rigid with a housing 6 of rectangular form. This housing encloses the

2

feeler-controlled mechanism of the unit, as will be later described, and which includes a horizontal shaft 7 journaled in the front and rear walls of the housing and normally disposed parallel to the wire 2.

At one end the shaft 7 projects out from the adjacent wall 8 of the housing, and a rigid probe finger 9, having a longitudinal slot 10 therein, is clamped adjacent one end on said end of the shaft and extends thence laterally out a distance sufficient to allow the probe finger to straddle the grade wire 2.

The finger 9, laterally in from the shaft 7, is provided with a longitudinally extending tapped stud 11 on which a counterbalance weight 12 is threaded. The finger 9, including the weight 12, is enclosed in a rigid casing 13 which is open to the housing wall 8 and is secured thereto by angle brackets 14. The casing is provided with longitudinal slots 15 matching the probe finger slot 10 but considerably wider, as shown in FIG. 1. Also, the height of the casing 13 is considerably greater than that of the probe finger 9, so as to allow of material swinging movement of the finger in a vertical plane without interference as the level of the machine relative to the grade wire 2 may vary.

The housing 6 and parts attached thereto are yieldably maintained in or returned to a position such that shaft 7 is parallel to the grade wire 2, as previously described, by means of a laminated leaf spring 16 which at one end is secured to the upper end of the stationary spindle 4 above the housing 6, as shown at 17, and at its free end projects between upstanding stop pins 18 on the housing.

The housing 6 is additionally yieldably held in its normal position by a spring-pressed detent 19 engaging a seat 20 in the sleeve 3 and mounted in connection with a screw 21 threaded through an ear 22 rigid with and projecting from the housing in overlying relation to the sleeve 4, as shown in FIG. 2.

By reason of the above described mounting and control of the probe finger 9, from the standpoint of rotation in a horizontal plane, the enclosed probe finger can readily pass by the various arms or brackets 23 which support the grade wire 2, as shown in FIG. 4.

It will be seen that when the casing 13 engages any such arm 23 as the machine advances, said casing and the housing 6 swing as a unit about the spindle 4 as an axis. The spring 16 is thus increasingly placed under tension; the detent of course moving out of the seat 20. When the casing 13 finally clears and moves past the arm 23, the spring 16 quickly returns the casing 13 and housing 6 to their initial position, with the probe finger 9 straddling the wire and the detent 19 reengaged in its seat 20 and holding the unit steady.

As the probe finger swings up or down with any variation in level between the machine-mounted housing 6 and the grade wire 2, the shaft 7 is rotated in one direction or the other. Such rotation in either direction closes a circuit which actuates the machine-level control mechanism in the same manner as shown in U.S. Patent No. 2,864,452. This circuit closing is effected by the use of oscillator coil units 24 and 24a, which are mounted in the housing 6 in spaced relation lengthwise of shaft 7.

For controlling one such circuit with an upward movement of the outer portion of the probe finger 9, the unit 24 is employed. In this case, shaft 7 is provided with a radially projecting vane 25 positioned to sweep between a pair of oscillator coils 26. The vane and coils, which are a part of unit 24, are arranged in connection with an electronic circuit and a power relay, indicated at 27, in the housing 6, and from which the necessary wiring (not shown) leads to the control mechanism above mentioned.

The units 24 and 24a are at present in commercial production and are available on the open market, being made for use in systems requiring an on-off electric control de-

vice to operate various types of equipment. In such a unit, the oscillator coils are physically aligned and connected to be regenerative. In operation, as the vane sweeps between the coils, their series inductance drops until at a sharp critical point oscillation stops. The grid associated with the unit loses its negative bias, causing a sudden gain in plate current, which powers the relay. When the vane is withdrawn from between the coils, oscillation resumes at the same sharp point, cutting off power to the relay.

For closing a control circuit upon downward movement of the outer portion of the probe finger 9, the separate oscillator coil unit 24a, identical with that above described, is employed; such separate unit including a vane 25a secured on shaft 7 and a pair of oscillator coils 26a between which vane 25a is adapted to sweep. The housing 6 is provided with a hinged door 28 so that easy access to the various parts in the housing, for adjustment or inspection thereof, is afforded.

As will be clearly evident from FIG. 3 of the drawings, the vanes 25 and 25a are adjustable on the shaft 7. This enables the range of action of the mechanisms controlled by vane movement to be readily varied as conditions may require.

In order to yieldably maintain the probe finger 9 in a normal or inactive position, without relying on the grade wire, a permanent magnet M is mounted in rigid and depending relation to the shaft 7 and cooperates with a similar magnet M¹ mounted in the housing 6 directly below the magnet M, as shown in FIG. 3. These magnets thus form a biasing means for the purpose.

FIGS. 6-8 illustrate a modified feeler unit for use in connection with the steering of the machine, as shown in Patent No. 2,907,398.

This unit comprises a depending bracket-supported shank 29 on the lower end of which a depending yoke 30 is secured. Horizontally pivoted, as at 31, on and depending from the yoke 30 is a cooperating yoke 32, which is secured to a depending rigid casing 33 of rectangular form in section.

Pivoted adjacent its upper end in the casing, as at 34, on a horizontal cross shaft 35 disposed at right angles to the axis of the yoke pivot 31 is a depending probe finger 36 having an elongated slot 37 to straddle the usual grade wire. A stabilizing weight 38 is rigidly mounted with the finger 36 above the pivot shaft 35. The casing 33 has slots 39 in its opposite sides to match the finger slot 37.

The pivot shaft 35 of the probe finger, and which is rigid therewith, projects from one wall 40 of the casing 33 and into a housing 41 secured to said wall. Fixed on shaft 35 within the housing 41 is a double-ended rocker arm 42 which overlies a pair of separate micro switches 43 mounted in the housing 41 in spaced relation lengthwise of the finger 36, and by means of which the steering of the machine is effected upon lateral swinging of the probe finger 36 to one side or the other, as set forth in said Patent No. 2,907,398. To actuate the switches alternately the rocker arm 42 is provided with projecting elements 44 positioned of course to engage the usual control buttons on such switches.

To limit swinging movement of the probe finger, so that no possible damage can be done to the switches, stop members 45 are adjustably mounted in the casing 33 on opposite sides of the probe finger 36.

When, upon forward travel of the machine on which the unit is mounted, the casing 33 engages a grade-wire supporting arm, said casing, together with yoke 32, swings about pivots 31 as an axis so that the casing can clear such arm. Such swinging is yieldably resisted, and the casing brought back to a normal position, by a vertical leaf spring 46 secured at its lower end in the yoke 32 at the bottom thereof, as at 47, and at its upper end engaging between stop elements 48 on yoke 30 at the upper end thereof. The yokes are yieldably held in normally aligned relation with each other by a spring-pressed

detent 49 mounted on one side of yoke 32 radially of the adjacent pivot 31 and engaging a seat 50 in the adjacent circular peripheral face 51 of the yoke 30, and which face is concentric with pivot 31, as shown in FIG. 8.

From the foregoing description it will be readily seen that there has been produced such a device as will substantially fulfill the objects of the invention, as set forth herein.

While this specification sets forth the present and preferred construction of the device, still in practice such deviations from such details may be resorted to as do not form a departure from the spirit of the invention, as defined by the appended claims.

Having thus described the invention, the following is claimed as new and useful, and upon which Letters Patent are desired:

1. A feeler unit for engagement with a grade reference member arranged to control the actuation of the operational-movement control mechanism of a traveling machine and which mechanism includes separate oscillator coil units; the feeler unit comprising a probe finger arranged to contact said member, a shaft extending lengthwise of the direction of travel of the machine fixed with the finger adjacent its inner end, a relatively stationary housing through which said shaft projects and in which the shaft is journaled, the oscillator coil units being mounted in the housing to one side of the shaft in spaced relation lengthwise thereof, and radial vanes fixed on the shaft within the housing in position to cooperate with and alternately sweep between the coils of the respective units upon swinging of the probe finger, with the resultant rotation of the shaft, in one direction or the other from a predetermined normal position.

2. A feeler unit for engagement with a grade reference member arranged to control the actuation of the operational-movement control mechanism of a traveling machine and which mechanism includes normally idle actuating units; the feeler unit comprising a probe finger arranged to contact said member, a shaft extending lengthwise of the direction of travel of the machine fixed with the finger beyond the member and projecting on one side of the finger, a support fixed relative to the swinging movement of the finger to one side thereof in which the shaft is journaled and on which said actuating units are mounted in spaced relation, and means included in part with said actuating units and functioning upon swinging of the finger and the accompanying rotation of the shaft in one direction or the other from a predetermined normal position to alternately place said units in operation.

3. A unit, as in claim 1, with means independently mounting the vanes on the shaft for rotary adjustment thereon whereby to vary the range of operational control of the mechanism.

4. In a feeler device for operation by a grade wire to control the actuation of the operational-movement control mechanism of a traveling machine and which mechanism includes normally idle actuating units, the feeler device including a swingable probe finger the swinging of which in one direction or the other from a predetermined normal position actuates said units alternately; the finger having a longitudinal slot to receive the grade wire therethrough, a support fixed relative to and from which the finger is swingably supported, and a rigid casing rigid with the support enclosing the finger and in which said finger is free to swing; the casing having longitudinal slots on opposite sides symmetrical to but materially wider than the finger slot.

5. In a feeler device for operation by a grade reference member to control the actuation of the operational-movement control mechanism of a traveling machine, the device including a movable probe finger to engage said member and whose movement relative to the member in a direction at right angles thereto actuates said mechanism, a support fixed relative to and from which the finger is supported, mounting means for the support including a

pivot element disposed at right angles to the longitudinal plane of the finger and about which the support is swingable, spring means between the support and said mounting means to yieldably resist such swinging of the support and to return the same to a predetermined normal position after being so swung; said mounting means including a stationary member having a peripheral face concentric with the axis of the pivot element, and a spring-pressed detent mounted on the support, said stationary member having a detent-receiving seat in said face positioned to receive the detent when the support is in said predetermined normal position. 10
